UNITED STATES PATENT OFFICE.

ROBERT JARDINE, OF DETROIT, MICHIGAN, ASSIGNOR TO RICH TOOL COMPANY, OF CHICAGO, ILLINOIS, A CORPORATION OF ILLINOIS.

VALVE.

Application filed January 2, 1925. Serial No. 40.

This invention relates to valves, and more particularly to valves for internal combustion engines.

One of the objects of the invention is the provision of new and improved means for preventing oxidation of the valve head of exhaust valves in gas engines during the operation of said engine.

Another object of the invention is the provision of a new and improved valve construction, parts of which will automatically expand to properly engage the valve seat to prevent leakage of the same.

Other objects of the invention are the provision of a new and improved valve that is possessed with the requisite amount of strength at all temperatures, is not affected by the oxidizing products of combustion, and one that is cheap to manufacture, simple in construction, and that is not likely to leak or get out of order during its operation.

Other and further objects and advantages of the invention will appear from the following description taken in connection with the accompanying drawings, in which

Fig. 1 is a vertical section of a valve showing the invention in position thereon;

Figs. 2 to 8 inclusive are similar views showing different forms of the device, respectively; and

Fig. 9 is a vertical section of the head and a portion of the stem of a still further modified form of the device, with parts broken away.

Exhaust valves for internal combustion engines are subjected to the oxidizing effect of the heated products of combustion, consequently the valves not only become very hot but they often develop leaks due to the oxidizing of the exposed surface of the heated material. The use of most non-oxidizing material for making the entire valve is prohibitive in practice on account of the cost of the material. The average non-oxidizing material is most suitable for the seat itself, but frequently in a red hot condition it lacks strength.

In the present invention the seat portion of the valve is protected from the oxidizing effects of the exhaust gases, and the main body

of the valve is composed of a material that more nearly retains its cold strength than the non-oxidizing material when the head and stem are subjected to high temperatures. In other words, the parts are so constructed that the valve retains the strength possessed by that of the usual construction and at the same time it has all the advantages of a valve made from non-oxidizing material.

The valve may take various forms or shapes, and it is understood that the forms of the device selected to illustrate embodiments of the invention are by way of examples only.

On the drawings the reference character 10 designates a valve stem which may be of the usual or any approved construction, and 11 the valve head. The head is secured to the stem in any suitable manner, as by being clamped between the shoulder 12 and the headed portion 13, as is usual in such constructions. If desired the stem may be welded to the head. The valve head is shown as being composed of a rigid disk, but it is understood that it may be otherwise. The valve head 11 is beveled to form the usual seat engaging surface 120.

Since the oxidizing of the seat-engaging portion of the valve is the part that is most vitally affected by the oxidation thereof, suitable means are provided for protecting this surface, or, in other words, suitable non-oxidizing material is employed for forming a valve seat-engaging portion. This material may be any of those now on the market and selling under the trade names "AES", "Stainless Steel", "Silcrome F," "Nicrome," "Silcrome No. 1" and the like which have relatively high percentages of nickel, chromium, silicon, or a combination of these elements.

In the forms of the device shown in Figs. 1 to 4, inclusive, the head 11 is provided with a protective covering which completely envelops and protects the entire exposed surface thereof. In Fig. 1 this is accomplished by providing a tapered cup or frustro-conical shaped member 14, which may be and preferably is a sheet metal stamping which is adapted to be mounted on the stem 10 between the shoulder 12 and the head 11 and contain said

head. The inclined surface 15 of the cup 14 is adapted to engage the valve seat. A disk 16, which may be of sheet metal, is mounted on the stem 10 between the headed portion 13 and the valve head 11. The peripheral edges of the cup and disk 16 are united in any suitable manner, but in order to form a heat conducting and radiating surface the edges are so connected as to form a projection 17. As shown, 5 the plate 16 has its edge rolled to form an annular ring or head 18 about which the edge 19 of the cup 14 is rolled. The projection 17 is arranged adjacent to the inclined surface 15, and is adapted to assist in conducting the heat 10 away from said surface and radiating or dissipating the same, thereby preventing overheating or burning of said surface.

In the use of a sheet metal envelope, if a leak in the valve develops the escape of the 20 heated gases during their expansion will cause a local expansion, outward of that portion of the envelope in proximity to the leak due to its increased temperature. This local expansion will automatically close the leak 25 and that portion of the envelope will not get any hotter, and consequently will not be likely to "burn".

The form of the device disclosed in Fig. 2 differs from that in Fig. 1 in that the tapered 30 cup or frusto-conical member 21 is placed on the outer instead of on the inner side of the head 11. The edge of the cup member 21 is rolled about the edge of the plate 22 to form a heat radiating fin or surface 23 similar to 35 the head 17 of Fig. 1.

The form of the device shown in Fig. 3 differs from that shown in Fig. 1 in that the peripheral edges of the cup member 24 and plate 25 are not rolled to form a heat radiating member. The peripheral edge of the cup 40 member 24 is merely flanged over the edge of the plate 25 as shown at 26.

In the form of the device shown in Fig. 4 the plate 27 is arranged on the inner instead 45 of on the outer side of the head 11, and the cup shaped member 28 is arranged on the outer side and is flanged over the plate 27 as at 29.

The forms of the device shown in Figs. 5 50 and 6 differ from those disclosed in Figs. 3 and 4 in that the plates 25 and 27 respectively are eliminated. In Fig. 5 the frusto-conical or cup shaped member 31 is secured on the inner side of the valve head 11 and is flanged over the outer side of said head, as at 32.

In Fig. 6 the corresponding cup shaped member 33 is secured to the outer side of the valve head and is flanged over the inner side of said head, as at 34.

60 In the form of the device shown in Fig. 7, the frusto-conical or cup-shaped member 35 extends about the inner face and seat-engaging surface of the valve head 11, and its outer edge terminates flush with the outer face of 65 the said head.

In Fig. 8 the frusto-conical or cup-shaped member 36 engages the outer face of the valve head 11, and the flange or inner edge of said member terminates flush with the inner face of said head. 70

It may be desirable to protect the valve seat portion and the entire outer end of the valve from the deleterious effect of the heated gases in the use of the valve in an internal combustion engine. As shown in Fig. 9, this is accomplished by providing an envelope 37 which extends over the entire outer surface of the valve and the valve seat portion 38, and is flanged over the under side of the plate 39 as shown at 41. Depressions 42 are formed 80 in the envelope for engaging the recesses 43 in the plate 39. The depressions 42 form recesses for the reception of a spanner wrench for rotating the valve as is common in such constructions. Where the valve stem 44 is 85 connected to the valve head or plate 39 by upsetting the outer end thereof, as shown at 45 in Fig. 9, it will be necessary to form a depression 46 in the envelope 37 for receiving the upset end 45. 90

It is thought from the foregoing taken in connection with the accompanying drawings that the construction and operation of my device will be apparent to those skilled in the art, and that various changes in size, 95 shape, proportion and details of construction may be made without departing from the spirit and scope of the appended claims.

I claim as my invention:

1. A valve for an internal combustion engine comprising a head, a stem therefor, and a protective covering for said head, said covering comprising an envelope composed of two parts having their edges rolled together to form a heat-radiating head. 100

2. A valve for internal combustion engines comprising a head, a stem therefor, an envelope of sheet metal for said head, said envelope comprising a plate for engaging one side of said head, a cup-shaped member for receiving said head, said member provided with a flange for engaging the outer surface of said plate adjacent to the peripheral edge thereof. 110

3. A valve for internal combustion engines, comprising a head provided with a beveled edge, a stem for said head, said stem being provided with a shoulder, and a protective covering of non-oxidizing material for the inner portion and beveled edge of said head, said covering being clamped on said stem between said head and shoulder, said covering having portions engaging the face of said head opposite said stem. 115

4. A valve for internal combustion engines comprising a head having a beveled valve seat engaging portion, a stem rigidly secured to said head, and an envelope of non-oxidizing material secured to said head for protecting the inner surface and beveled portion of 120 125 130

said head, the free edge of said envelope being flanged over the outer surface of said head.

5. An exhaust valve for an internal combustion engine comprising a head having a bevel surface, a stem for said head, an envelope of non-corrosive sheet metal completely enclosing said head and having a portion conforming to said bevel surface for forming

a valve seat engaging portion, said envelope forming a gas-tight connection between the same and said stem whereby said head will be completely protected from contacting heated gas passing by said valve during its operation in a combustion engine. 15

In testimony whereof I affix my signature.

ROBERT JARDINE.
